JOHN PENROD AND ROBERT D. THOMPSON, OF OKMULGEE, OKLAHOMA.

WELL PUMP.

1,425,276.

Specification of Letters Patent. Patented Aug. 8, 1922.

Application filed August 24, 1921. Serial No. 494,846.

To all whom it may concern:

Be it known that we, JOHN PENROD and ROBERT D. THOMPSON, citizens of the United States, and residents of Okmulgee, in the county of Okmulgee and State of Oklahoma, have invented certain new and useful Improvements in Well Pumps, of which the following is a specification.

Our present invention relates usually to pumps for use in driven wells and is more particularly designed for use in connection with oil wells where the presence of sand with the oil usually renders it necessary to frequently replace valve seats and pump leathers and the like.

Our primary object is the provision of a pump which may be placed within the casing of a well without the necessity of a pump tube and which may be adapted in place at any desired point within the well casing and clutched at that point until its removal for one reason or another becomes essential. A further object is the provision of a pump of this type which may be just as readily and easily removed, which is capable of ready repair when once removed and which for these purposes and reasons is particularly desirable and applicable for use in wells that have large volumes of oil and have ceased flowing due to insufficient natural gas pressure.

In the accompanying drawings which illustrate our present invention and form a part of this specification,

Figure 1 is a sectional view through a well casing and through the upper portion of our improved pump loosely therein prior to anchoring.

Figure 2 is a similar view through another portion of the well casing showing the lower portion of our improved pump in place.

Figure 3 is a view similar to Figure 1 showing the anchor means in effective position.

Figure 4 is an enlarged detail section through the cable coupling member.

Figure 5 is an enlarged cross section taken on line 5—5 of Figure 3, and

Figure 6 is a detail perspective view taken on an enlarged scale of the clutch ring and one of the clutching anchors.

Referring now to these figures, we have shown in Figures 1, 2 and 3 the cylindrical casing A of a driven well, as for instance, an oil well, within which our improvements

are designed to operate without the use of a pump tube ordinarily employed within the casing and which as well known requires step by step jointing and unjointing in its insertion and removal so that these operations are both lengthy and tedious and become decidedly disadvantageous especially in those oil wells where sand abounds in great quantities in the oil, requiring the removal of cup leathers and frequently of the valves and other sections at comparatively short intervals.

In our improved arrangement a pump barrel is utilized within the lower enlarged portion 10 of which the piston 11 operates above the lower intake or standing valve 12, the latter secured in connection with a shoe 13 at the lower end of the barrel above the perforated intake member 14. It is to be understood that so far as our invention is concerned the pumping member, for instance, piston 11 may be of any suitable type, various types now in use being adaptable with almost equal facility, and it is to be further understood that the type of piston we have shown is for illustration only, its upper valve 15 permitting upflow of fluid through the pump upon each downward stroke of the latter so as to lift, during each downward stroke, that fluid sucked up through the standing valve 12 upon the previous upward stroke of the piston.

To the piston 11 is connected the lower end of a pump rod 16 passing upwardly through the upper reduced portion 17 of the pump barrel, the latter of which is connected at its lower end with the lower enlarged portion 10 of the barrel by a reducer 18 and a cylindrical relief valve housing 19 having a tapering end surface 20 adjacent to its lower end provided with radial openings 21 through its wall. A conical relief valve 22 is lengthwise slidable within the housing 19 above the upper end of the lower enlarged portion 10 of the pump barrel and normally seats against the tapering inner surface 20 under tension of a spring 23 compressed within the housing 19 between the relief valve 22 and the reducer 18.

The reducer 18 is connected to the lower end of the upper portion 17 of the pump barrel by a coupling ring 24 which forms a support for the lower end of a spring 25 coiled around the barrel and the upper end of which supports a clutch actuating ring 26, this ring being freely slidable on the bar-

rel 17, below the clutch supporting ring 27, the latter of which is also slidable upon the pump barrel.

The ring 27 is provided with upstanding bearing members 28 at spaced points there-around, as is best seen in Figure 6, upon which bearing members are pivotally connected the lower ends of links 29 whose upper ends are in turn pivotally connected to the lower ends of the clutching or anchor members 30 having outer inclined and toothed surfaces 31, and having inner dove tailed grooves 32.

The several clutch or anchor members 31 are movable into and out of the effective position upon the external surface of a slide 33 movable on the upper portion of the barrel 17 between stationary collars 34 and 35. This slide 33 has an outer tapering surface 36 provided with outstanding dove tailed ribs 36, which the dove tailed grooves 32 of the clutch or anchor members 30 receive, so that in their movement with respect to the slide, these clutching members or anchors 30 will be guided by the ribs and as the clutch members move upwardly along the surface of the slide they will be shifted outwardly by virtue of the tapering outer surface of the slide.

At its upper end the slide 33 engages a compressible ring 37 around the pump barrel whose upper end abuts a head 38 rigidly secured to the upper end of the pump barrel.

As will be seen by reference to Figures 1 and 3 the pump rod 16 passes upwardly through the relief valve 22 and through the upper reduced portion 17 of the barrel in spaced relation to both of these parts so that there is left a free passage for the upward movement of the fluid around the pump rod into the well casing A above the pump barrel.

The clutch actuating ring 26 is a member of considerable weight whereby when, during the lowering movement of the pump barrel into the well casing this movement is suddenly checked, the clutch actuating ring 26 will move downwardly on the barrel 17 against the tension of spring 25 and will compress this spring to such an extent that the rebound of the spring will shift the ring 26 upwardly into forceful engagement with a clutch supporting ring 27, throwing the latter upwardly with its clutch or anchor members 30 whereby the latter will slide upwardly and outwardly on the slide member 30 into engagement with the inner surface of the well casing A.

For the above purpose it will be understood that in lowering the pump into the well casing in the first instance the parts will be in the position shown in Figure 1 with the slide 33 in lowermost position against the lower stop collar 34, and means employed

being the same means subsequently utilized 65 to impart reciprocating movements of the pump rod and its piston.

Thus a cable 39 may be utilized, its lower end passing through the upper axial opening 40 of a cable connecting member 41, and the lower end of the cable being permanently secured within a rectangular block 42 shiftable into and out of a rectangular socket of the member 41 through its side opening 43 and normally held in place within said socket by a set screw 44. Thus turning movement of the cable 39 will be communicated to the cable connecting member 41, the latter of which has a depending internally threaded portion 45. On the upper shouldered end of the pump rod 16 is a flanged rotating sleeve 46 threaded into the depending portion of the cable connecting member 41 with its upper surface opposing the lower surface of a head 47 rigidly secured upon the upper end of the pump rod. Anti-friction balls 48 provide for free rotation of the cable connecting member with respect to the upper end of the pump rod, such balls being disposed as shown in Figures 1 and 3 between the collar 46 and the head 47 of the pump rod, so that all twisting and turning movement of the cable 39 will thus be taken up with minimum wear of the parts and without turning movement of the piston 11 which would have the effect of causing too great wear of the latter.

Adjacent to its lower end the pump rod 16 has an annular rib 49 as plainly seen in Figure 2 which is movable upwardly 100 through the lower end of the relief valve housing 19 and into engagement with the lower end of the relief valve 22 as shown in dotted lines in Figures 3 and 6, rib 49 being spaced above a lower and somewhat larger rib 50 of the pump rod provided with notches 51 to admit of free passage of fluid thereby and adapted upon engagement, during upward movement of the pump rod, with the lower end of the relief valve housing 19 which forms an annular shoulder within the upper end of the lower enlarged portion 10 of the pump barrel.

Thus in lowering the pump within the well casing A by means of the cable 39 and with the parts in the position shown in Figure 1, the compressible sleeve 37 being in the normal extended position, the weight of the pump barrel and its parts is sustained through the pump rod 16 and its lowermost collar 50 in engagement with the lower shouldered end of the relief valve housing 19. When the pump has reached to the point where it is desired to be anchored for operation, the cable 39 is abruptly snubbed and in the arrested movement of the pump barrel and its parts due to this sudden snubbing of the cable, the clutch

actuating ring 26 moving downwardly of its own inertia against the tension of the spring 25 as above described with a result that this spring is compressed and 5 then rebounds, moving the clutch actuating ring 26 upwardly into engagement with the clutch supporting ring 27 so as to force the latter with its several clutches or anchor members 30 upwardly and outwardly along 10 the slide 33 and into engagement with the inner surface of the well casing A so that these clutches or anchor members 30 will thereafter sustain the weight of the pump rod and its parts by virtue of their downwardly inclined teeth 31 in contact with 15 the well casing. Thus when the pump rod is again slightly lowered, the barrel and its parts supported now by the clutch members 30 will move downwardly through the slide 33 compressing the sleeve 37 between the slide and the barrel head 38 until this sleeve is extended laterally by such compression into firm, even and uniform contact with the inner surface of the well casing A so as to prevent downward passage of fluid past this sleeve. 20

Thus the parts will in active position assume the position shown in Figure 3 and it is simply necessary to continue lowering 25 movement of the pump rod 16 to such a point that its plunger will move upwardly and downwardly in operation between the lower standing valve 12 and the relief valve housing 19 without engaging either of these parts. Thus as the piston 11 moves upwardly fluid will be sucked upwardly through the perforated intake member 14 and upwardly through the standing valve 12 within the lower portion 10 of the barrel 30 below the pump and upon each downward movement of the piston this fluid will be forced upwardly through the piston and through its valve 15 and from thence upwardly around the piston in and through 35 the reduced portion 12 of the barrel into the well casing A above the pump.

It is obvious that the clutch or anchor members 30 support the pump barrel in the active position against downward movement and do not prevent the barrel from upward movement, which frictional engagement of the compressed sleeve 27 with the well casing and the weight above the pump alone prevents, and it thus becomes 40 obvious that when the pump is to be pulled upwardly out of the well, elimination of excessive strain upon the cable 39 depends upon relief of the weight of the fluid upon the pump. It is for this purpose that the 45 pump rod 16 has a collar 49 engageable with the lower end of the relief valve 22 as the pump rod is drawn upwardly beyond the limit of its normal up stroke in drawing the pump from the well. Upon 50 such engagement of the rib or collar 49 of

the relief valve 22, the latter held seated by its spring 23 to close the openings 29 leading through the well to the relief valve housing, is lifted from its seat so that the fluid above the pump may find its way 55 downwardly through the upper portion of the barrel and then outwardly through the openings 21 into the well casing A around the lower end portion 10 of the pump barrel. Then further upward movement of the 60 pump rod 16 after the weight of fluid about the pump is relieved, causes engagement between the lowermost collar 50 of the pump rod and the lower shouldered end of the relief valve housing so that the pump barrel 65 will be lifted and as the clutch or anchor members 30 shift downwardly the slide 33 will also be free so that it may shift downwardly and relieve distending pressure against the flexible sleeve 37. 70

It is thus obvious that our invention is particularly advantageous in connection with those wells requiring the frequent removal of the pump for cleaning and repairing as well as those wells requiring frequent swabbing, on account of its adaptability to extremely easy and quick installation and removal, and that while as shown the pump is limited to use in more or less shallow wells where the weight of fluid above the pump 75 barrel can be lifted by means of a cable such as the cable 39, it is to be observed that the cable connecting member 41 has an upper reduced and externally threaded portion 52 which may be utilized to connect the lower 80 end of a plunger actuating rod or tube in place of the cable. 85

We claim:

1. In a pump for well casings, a barrel, a pump rod extending through the barrel and 90 leaving a fluid outlet space between the same and the barrel, a standing valve at the lower end of the barrel, a valved plunger within the lower portion of the barrel connected to said rod, said barrel including a portion engageable by the pump rod upon upward movement of the latter beyond the normal upward limit of its stroke, provided with an internal tapering portion forming a valve seat and having apertures therethrough, a 95 ring shaped tapering valve member around the rod normally seated downwardly on said seat and controlling the several apertures, and means carried by the pump rod to unseat the said valve prior to engagement of 100 the rod with the barrel for lifting the latter. 110

2. In a pump for well casings, a barrel having automatically active means in connection with its upper end for laterally shifting movement into fluid tight engagement 115 with the inner surface of a well casing and having a relief valve housing adjacent to its upper end provided with a lower internal annular shoulder and a tapering internal valve seat above the shoulder, and also pro- 120

vided with apertures extending through its wall from said seat, fluid valves in the lower portion of the barrel, a plunger movable in the lower portion of the valve, a rod connected to the plunger and extending upwardly through the barrel and forming a fluid channel between the same and the barrel, a tapering valve ring around the rod and seated downwardly on said valve seat to normally close the inner ends of

said apertures, said rod having means to engage and unseat the said valve upon upward movement of the rod beyond the normal stroke of the plunger, and means also on the rod to engage a portion of the barrel upon upward movement of the rod subsequent to the unseating of said valve.

JOHN PENROD.
ROBERT D. THOMPSON.
